J. RIGANTE

SHOE TREE

Filed March 5, 1924

INVENTOR
J. Rigante
BY
F. Ledermann
ATTORNEY

UNITED STATES PATENT OFFICE.

JOSEPH RIGANTE, OF MINEOLA, NEW YORK.

SHOE-TREE.

Application filed March 5, 1924. Serial No. 696,941.

To all whom it may concern:

Be it known that I, JOSEPH RIGANTE, a citizen of the United States, residing at Mineola, in the county of Nassau and State 5 of New York, have invented certain new and useful Improvements in Shoe-Trees, of which the following is a specification.

The main object of this invention is to provide a shoe tree used in the stretching of 10 shoes or shaping of the same, the principal purpose being to provide a tree which may have its length extended so as to fit various sizes of shoes. The art, as at present known, requires that shoe trees be of the same size as 15 the shoe being stretched. Thus in establishments it is required that a variety of sizes of shoe trees be carried, whereas with this device, one shoe tree for any or all sizes is sufficient.

Another object is to provide a shoe tree 20 having an extensible toe member, this toe member being extended when the shoe tree is spread apart to fit a larger and wider shoe interior.

These and other objects will become apparent in the description below, in which characters of reference refer to like-named parts in the drawing.

Referring briefly to the drawing, Figure 1 is a sectional elevational view taken 30 centrally thru the entire shoe heel, and shows the mechanism by which the device may be operated.

Figure 2 is a top plan view of the same.

Figure 3 is a top plan view showing the 35 toe extended and the hand wheel by which the toe is extended and the side spread, cut away.

Figure 4 is a schematic plan view, showing the mechanism used in extending and spreading the shoe tree.

Referring in detail to the drawing, the numerals 10 and 11 represent the main bodies of the shoe tree. The substantially parallel 45 and mutually adjacent faces are inclined divergently. Each of the body members has a surface 12 and a surface 13, these surfaces being inclined toward the center of the shoe, providing a tapering channel 14 which is 50 widest at a point intermediate the length of the bodies. The rear ends of these bodies have hinges 17 mounted thereon to which the heel member 16 of the shoe tree is hingedly attached. This heel member is provided with a lifting hook 18 on its surface 55 by means of which said member may be

lifted upwardly out of a shoe. In the body member 10, a longitudinal recess 19 is provided in which a rack bar 20 is slidably retained. The forward end of the rack bar 60 has an offset arm 21 which extends toward the opposite body member 11, and at a point in the channel 14, a ball 22 projects from the arm. An additional rod 23 extends forwardly 65 from said ball and is connected to a toe shell 24. A semi-circular recess 25 is formed in the body above the recess 19. This semi-circular recess houses a gear 26, the latter being in continual mesh with the rack bar 20. Said gear is rigidly mounted on a shaft 70 27 to which a small bevelled pinion 28 is attached. A shaft 29 having a pinion 30 at its lower end, which engages and meshes with the pinion 28, is journaled in the body 10 adjacent the rack bar and has a hand wheel 31 at its upper end, this hand wheel 75 being used to rotate the shaft 29.

In using the device, the heel member 16 is lifted upwardly so that the body portions 10 and 11 may be readily inserted into 80 a shoe. The device is inserted into a shoe when the toe shell 24 lies adjacent the forward end 32 of the body members, this position being shown in Figure 1. When the shoe tree has been placed in the shoe and the heel rotated to its proper position, the hand wheel is rotated in the required direction. As the hand wheel is rotated, longitudinal movement is imparted to the rack bar 20 85 thru the medium of the gears 26, 28, and 30. 90 The movement of the rack bar causes the ball to ride on the forward surfaces 12 of the bodies 10 and 11 and spreads the same apart, thus stretching the width of the shoe. Simultaneously with this spreading, the toe 95 shell 24 is extended so that the shoe sole at the toe end is prevented from buckling or bending as usually occurs. When the shoe has been sufficiently stretched, the hand wheel 31 is rotated in the opposite direction, 100 causing the rack bar to move the ball 22 rearwardly until it arrives at the greatest width of the channel 14, when the shoe tree may be easily removed from the shoe.

I claim:—

1. A shoe tree comprising a pair of body members arranged mutually adjacent, the mutually adjacent surfaces having a tapering channel therein, the channel being widest at a position intermediate its length, a rack bar, a toe shell, a rod integral with the rack bar and rigidly connected to the toe shell,

said rack bar when moved forward being adapted to extend the toe shell, a ball on said rack bar normally located at the widest portion of the channel, said rack bar when extended being adapted to spread the body members apart by engaging the tapering sides of the channel, a shaft, a gear on said shaft engaging the rack bar, a bevelled pinion adjacent said gear, an additional shaft extending angularly, the pinion gear at its lower end engaging the pinion gear of the first-named shaft, and a hand wheel at the upper end of said last-named shaft to rotate the latter.

15. 2. A shoe tree comprising a pair of body

members arranged mutually adjacent, the adjacent surfaces having forwardly tapering channels therein, a rack bar, one of said bodies having said rack bar slidably mounted therein, a toe shell adapted to cover the tips of the body members, a rod connecting the toe shell and rack bar, a ball member integral with the rack bar and engaged in the tapering channels, said rack bar when extended being adapted to simultaneously advance the toe shell and spread the body members apart, and means for moving said rack bar.

In testimony whereof I affix my signature.

JOSEPH RIGANTE.
